LASTING-MACHINE.

SPECIFICATION forming part of Letters Patent No. 726,087, dated April 21, 1903.

Application filed August 6, 1902. Serial No. 118,573. (No model.)

To all whom it may concern:

Be it known that we, THOMAS H. MCAULIFFE and JOHN W. HOGAN, citizens of the United States, residing at Lynn, in the county of Essex and State of Massachusetts, have invented an Improvement in Lasting-Machines, of which the following description, in connection with the accompanying drawings, is a specification, like letters on the drawings representing like parts.

This invention relates to what is commonly known as the "Hand-Method Lasting-Machine"—such, for instance, as is illustrated in United States Letters Patent Nos. 584,744, 696,717, and 696,740.

As explained in Patent No. 584,744, preparatory to the lasting operation the parts of the boot or shoe are applied to the last in usual manner and the edge of the upper at the toe and at the ball on each side of the last and sometimes also at the heel is pulled over the bottom of the last and the inner sole and is secured in each of said places by a tack or other fastening device. This constitutes the operation of "pulling over" the shoe.

In the operation of lasting the shoe is held by the operator and turned to present the different parts of the upper to an upper-manipulating mechanism, shown as a pair of pincers, which operate automatically to seize the edge of the upper and pull the same over the bottom of the last and the inner sole.

In the machine shown in Patent No. 584,744 a tack supplying and driving mechanism is employed which operates to secure to the inner sole the successive parts of the upper acted upon by the upper-manipulating mechanism, whereby the lasting operation as a whole is carried out progressively by repeated operations of the upper-manipulating and fastening-driving mechanisms acting upon different parts of the upper at different times.

Patent No. 696,717 illustrates a lasting-machine having mechanisms for progressively placing a binder of wire or of a similarly-continuous material in binding relation with the successively-lasting parts of the upper, particularly at the toe portion of the shoe, said

wire being employed at certain parts of the shoe to hold the upper material in place instead of the usual tacks. In the machine shown in said Patent No. 696,717 the binder is fastened at its free end to a tack driven into the inner sole, and as each successive part of the upper is manipulated or pulled into place it is held temporarily by the strain of said binder until by repeated operations of the machine the whole toe part of a shoe is lasted, after which the binder, still strained tightly around the worked-over portions of upper, is secured to a tack driven into the inner sole on the side at which the lasting was completed.

In lasting-machines as heretofore constructed it has been customary to employ a reciprocating presser in stretching and laying down the edge portion of the upper around the toe of the shoe. The reciprocating presser was moved over the stretched portion of the upper to force the upper into the angle of union between the feather-edge and the lip of the inner sole in the position in which it was to be secured, first temporarily by the tacks or by a binder, such as the wire above referred to, and finally by the line of permanent stitching passing through the welt, upper, and the lip of the inner sole. The presser in the form of machine referred to was retracted out of contact with the upper between the successive operations of the grippers. It has been found in practice that the operation of such a reciprocating presser is not satisfactory in all respects. When the presser is moved forward, it frequently strikes the upper on the edge of the last opposite the edge of the inner sole and mars the upper, often breaks and mutilates the feather-edge, and sometimes forces the inner sole back from the edge of the last. The reciprocating presser occasionally tears the stretched portion of upper as it moves forward to push it into said angle of union between the feather-edge and the lip of the inner sole. This is particularly apt to occur if the upper is of thin or light material or consists of enameled or patent leather. Another objection to a recipro-

cating presser is that when it is retracted out of engagement with the upper the upper tends to slip back more or less. To obviate these disadvantages we have provided a presser or wiper adapted for use in lasting the toe portion of an upper which may be moved into operative position at the beginning of the toe-lasting operation and which will remain constantly in engagement with the upper until the lasting of the toe is completed, advancing from one worked-over portion of upper to another as the lasting operation proceeds.

We have constructed our wiper as a roll, the lower surface and periphery of which are adapted to engage the upper and force it squarely into the said angle of union. When a binder of wire or similar material is employed, the wiper is adapted to engage the wire and force it into position to place and hold the upper in the angle of union. We have so mounted our wiper that it may be moved into operative position at the will of the operator, and it will remain in this position during successive operations of the lasting-machine, and it may again be moved into inoperative position at the will of the operator.

Our rotary wiper has the advantage that it remains constantly in engagement with the upper and does not release the stretched-over portion of upper between the operations of the stretching mechanism, therefore insuring that the said stretched portion of upper will not slip back. It does not mar the upper adjacent to the edge of the last or force back

the inner sole from the edge of the last.

There is no danger in using the rotary wiper of breaking or mutilating the feather-edge. The rotary wiper also forces the upper into the angle of union and lays the successive portions of the binding-wire into position to hold the upper in a more certain and satisfactory manner than a reciprocating presser can do. The rotary wiper also has the advantage that there is no danger in its use of tearing the stretched portion of upper as the wiper operates to force the said stretched portion of upper into the angle of union, because the wiper is continuously in engagement with the upper and advances around the toe of the shoe as the lasting progresses, and the disadvantages above set forth resulting from the back-and-forth movement of the reciprocating presser are entirely obviated.

We have also provided a novel form of gage or support against which the edge of the shoe being lasted is adapted to be held during the lasting operation and which is particularly adapted for use with the rotary presser herein described.

Referring to the drawings, Figure 1 is a plan view of a part of the machine shown in the said patents with our invention applied in one of the best ways now known to us. Fig. 2 is a similar view of the part, showing the wiper in inoperative position. Fig. 3 is a plan view of the rotary wiper and its operative parts. Fig. 4 is a bottom plan view

thereof. Fig. 5 is a side elevation. Fig. 6 is a section on the line $x-x$, Fig. 3.

In applying our invention to lasting-machines, such as shown in the patents referred to, we prefer to employ as a means for supporting our improved wiper a slide similar to the reciprocating bars to which the pressers of said patents are attached, the said wiper taking the place on the slide that the reciprocating presser of said patents occupied. It will be understood, however, that our improved wiper may be supported in any other way without departing from our invention, so long as it is supported so as to be capable of operating as hereinafter described.

In the drawings, B represents a portion called the "intermediate plate" of the head of the machine on which the operative parts 85 are supported.

X^{16} designates a slide, which is similar to the reciprocating bars in the said patents above referred to. The position of the said slide to render the presser operative or inoperative is controlled by the cam-slide X^{23} , which is actuated by the lever X^{33} by means of a knee-lever. For a more complete description of the operation of these parts reference is made to Patent No. 584,744, above mentioned.

The wire 20 is supported upon a reel 2, which in turn is secured to the plate B, as shown in said Letters Patent No. 696,740, the wire being guided by a wire-holder 28 of usual construction.

To the end of the slide X^{16} is secured a plate or supporting member 4, to which an arm 5 is pivoted, as at 6. The arm 5 supports our improved wiper 7, herein illustrated as a disk 105 which is loosely pivoted to the arm and is adapted to have a continuous rolling engagement with the upper or the wire to force the same into the angle of union of the feather-edge and lip 26 of the inner sole, as will be presently described. The improved wiper herein shown is what may be called a "rotary" wiper. To support the shoe, we have provided a yieldingly-sustained gage 8, against which the side of the shoe is adapted to be held during the lasting operation, as best seen in Fig. 5.

Fig. 1 shows the rotary wiper in operative position, and in performing the lasting operation the wire 20 is secured at one end to a tack 10, and the shoe is held by the workman against the gage 8, the rotary wiper extending over the bottom of the last and engaging the upper and preferably the wire also, as seen in Fig. 5. When now the pincers 40 operate to manipulate the upper material, as described in the patents referred to, to draw the same over the last and the workman turns the last, the wiper 7 by its continuous rolling engagement with the upper and its contact with the binding-wire serves to hold the upper tightly drawn over the last and to cause the binder or wire to crowd the upper into the said angle of union of the feather-edge and

lip 26 of the inner sole and prevents any slipping back of the upper material, which is likely to occur during the backward movement of the reciprocating presser.

- 5 It sometimes happens that the edge portion of the inner sole, called the "feather-edge," which projects beyond the lip varies in width at different portions of a shoe, and in order that the shoe may at all times be presented 10 in position to have the wiper force the upper against the lip of the inner sole we prefer to sustain the gage 8 so that it may yield transversely to the axis of the wiper to accommodate different widths of feather-edges. One 15 convenient way of providing for the yielding movement of the gage is to provide the arm 5 with a depending stem 12, carrying at its lower end a collar 14, to which the lower end of the gage 8 is hinged, as at 13. A second 20 collar 15, having arms 16 projecting therefrom, is mounted to slide upon the stem 12 and is sustained in its normal position by means of the spring 17. Pins 19, projecting rearwardly from the gage, pass loosely through 25 apertures in the arms 16, and springs 21, surrounding said pins, serve to hold the gage normally forward.

From the above description it will be seen that if for any reason the projecting portion 30 of the sole varies in width the gage will yield backwardly against the action of the springs 21, thereby to allow the wiper to force the upper into said angle of union of the feather-edge and the lip of the inner sole and to maintain its engagement with the binding-wire. 35 Since the pins 19 are rigid with the gage 8, the backward movement of the gage causes a slight vertical movement of the collar 15.

To provide for a sufficient turning movement of the gage to allow the latter to accommodate itself to the contour of the shoe, the collar 15 is slotted, as at 22, and in said slot 40 plays a pin 23, projecting from the stem 12, the said pin serving as a stop to limit the 45 turning movement, which may be an amount equal to the width of the slot.

Upon again referring to the patents above mentioned it will be seen that the wire-placing mechanism is used only in lasting a portion 50 of the shoe, usually the toe, and it is necessary, therefore, to provide suitable means for throwing the wire-placing mechanism into and out of operation while the shoe is being lasted. As one means that may be 55 employed for throwing the wire-holder 28 into and out of operation we have chosen herein to show a mechanism operated from the slide X²³, as in Patent No. 696,740. It is of course necessary also to provide means to throw the 60 rotary wiper into and out of operative position, as the wiper is used whenever the wire-holder is used.

In order to throw the wiper out of operative 65 position when it is not needed, we prefer to provide means whereby when the slide X¹⁶ is withdrawn, as shown in Fig. 2, the arm 5, to which the rotary wiper is pivoted, is swung

into the position shown in Fig. 2 and in dotted lines in Fig. 3. As one means that may be employed for thus swinging the wiper into 70 and out of operative position by the movement of the slide X¹⁶ we have in this embodiment of our invention herein illustrated shown a rack and gear mechanism. The arm 5 has rigid therewith at its under side a gear 75 30, which meshes with a gear 31, carried by the plate 4.

Rigidly secured to the plate B is a rack 34, which engages the pinion 31, said pinion having a long face, as shown in Fig. 5, for this 80 purpose. The position of the rack 34 is shown in Fig. 5.

From this description it will be obvious that when the slide X¹⁶ is withdrawn such movement will roll the pinion 31 over the rack 34, 85 thereby rotating the pinion in the direction of the arrow, Fig. 3, and this rotation will be communicated to the gear 30, which will be carried in the opposite direction, as shown by the arrow, Fig. 3. Since the gear 30 is 90 rigid with the arm 5 and concentric with its pivot 6, the arm will be turned into its inoperative position. A reverse movement of the slide X¹⁶, caused by the movement of the cam-slide X²³, as described in said Patent No. 95 584,744, will throw the arm 5 into the full-line position, Figs. 3 and 1, which is the operative position. The arm 5 will be cut away, as at 36, and the narrow portion so left will engage the projecting end of the screw 37, 100 used to fasten the plate 4 to the slide, said screw acting as a stop to limit the movement of the arm and to maintain the wiper in operative position.

We believe that we are the first to devise 105 a lasting-machine which includes upper-manipulating mechanism constructed to act on different portions of the upper successively, combined with a wiper having a continuous advancing engagement with the upper, and 110 also the first to employ a wiper acting continuously on a binder to force the binder progressively into binding relation with the successively-manipulated parts of the upper, and therefore we intend to claim such a wiper 115 broadly.

By the term "upper-manipulating mechanism" we intend to include any means for stretching, pulling, or fitting the upper to the last and laying the edge of the upper over the 120 last, and by the term "binder" we intend to include a wire or equivalent flexible material. It will be obvious that the particular construction of the mechanism shown is not essential to our invention, as the same may 125 be varied or modified by those skilled in the art without departing from our invention.

We have shown our invention as applied to the lasting of welted shoes and have herein referred to the sole as an "inner sole," and to 130 the projection on the sole as a "lip." Our improved construction of lasting-machine may of course be used in lasting shoes in which the sole is provided with a shoulder instead of

with a lip between the feather-edge and the body of the sole. It is also adapted for use in lasting turn-shoes, in which the upper is secured to the sole instead of to the inner sole. By the term "lip" we therefore mean the projection, rib, or shoulder on the sole of a shoe being lasted, to which projection or shoulder the upper is later to be secured.

Having fully described our invention, what we claim as new, and desire to secure by Letters Patent, is—

1. A lasting-machine comprising means to manipulate different parts of the upper successively and a wiper constantly in engagement with the upper to force the edge portion of the successively-manipulated parts of the upper into the angle of union of the feather-edge and the lip of the inner sole.

2. A lasting-machine comprising upper-manipulating mechanism and a rotary wiper to force the edge portion of the manipulated upper into the angle of union of the feather-edge and the lip of the inner sole.

3. A lasting-machine, comprising means to manipulate different parts of the upper successively, mechanism for supplying binding material and a wiper constantly in engagement with the upper to place said material in binding relation with the successively-manipulated parts of the upper.

4. A lasting-machine, comprising upper-manipulating mechanism, means for supplying binding material and a rotary wiper to place said material in binding relation with the manipulated upper.

5. A lasting-machine, comprising means to manipulate different parts of the upper successively, a wiper constantly in engagement with the upper and acting on the successively-manipulated parts thereof separately to force the edge portion of the manipulated upper into the angle of union of the feather-edge and the lip of the inner sole, and means to put said wiper into and out of operative position as desired.

6. A lasting-machine, comprising upper-manipulating mechanism and a wiper constantly in engagement with the upper to force the edge portion of the manipulated upper into the angle of union of the feather-edge and lip of the inner sole, and a gage against which the last may be held during the operation of the wiper.

7. In a lasting-machine, means for working an upper over a last, a rotary wiper for placing a wire in binding relation with the over-

worked upper, a gage against which the last may be held during the operation of the wiper, and yielding means to sustain the gage for movement transversely of the axis of the wiper.

8. In a lasting-machine, upper-manipulating mechanism, a rotary member for forcing the upper into the angle of union of the feather-edge and lip of the inner sole, and a yielding-sustained gage mounted for turning movement about an axis parallel to the axis of the wiper, the gage being adapted to sustain the shoe during the operation of the wiper.

9. In a lasting-machine, upper-manipulating mechanism, a slide having an arm pivoted thereto, a rotary wiper carried by said arm, means to advance and retract the slide as desired, and means whereby the movement of the slide causes the wiper to be brought into and out of operative position.

10. In a lasting-machine, means for overworking the toe portion of an upper, a slide having an arm pivoted thereto, a rotary wiper carried by said arm, a stationary rack, and gearing between said rack and slide, whereby as the slide is moved longitudinally the wiper is brought into or out of operative position.

11. In a lasting-machine, means for working an upper over a last, a pivotally-mounted arm, a rotary wiper carried thereby and adapted to have rolling engagement with the upper to force it into the angle of union of the feather-edge and lip of the inner sole, a stem depending from said arm, and a gage yieldingly supported from said stem and also mounted to have a turning movement thereabout, said gage operating as a rest against which the last may be held.

12. A lasting-machine comprising mechanism for manipulating different parts of the upper successively, and a wiper having a continuous advancing engagement with the upper to force the edge portion of the successively-manipulated parts of the upper into the angle of union of the feather-edge and lip of the inner sole.

In testimony whereof we have signed our names to this specification in the presence of two subscribing witnesses.
